UNITED STATES PATENT OFFICE

104,252

DESIGN FOR AN AUTOMOBILE HEATER

John E. Goerlich, Toledo, Ohio

Application September 25, 1935, Serial No. 58,691

Term of patent 7 years

To all whom it may concern:

Be it known that I, John E. Goerlich, a citizen of the United States and residing at Toledo, in the county of Lucas and State of Ohio, have invented a new, original, and ornamental Design for an Automobile Heater, of which the following is a specification, reference being had to the accompanying drawing forming a part thereof.

In the drawing:

Figure 1 is a front perspective view of an automobile heater showing my design.

Figure 2 is a front elevation view of the heater.

Figure 3 is a side elevation view of the heater.

The characteristic feature of my design resides in the series of vertically disposed spaced ribs extending from the top to bottom of the heater shell, exposing the rectangular section of the radiator core between the shutters.

I claim:

The ornamental design for an automobile heater, substantially as shown and described.

JOHN E. GOERLICH.
